UNITED STATES PATENT OFFICE.

EDWIN C. WASHBURN, OF MINNEAPOLIS, MINNESOTA.

DRAFT-RIGGING FOR CARS.

No. 805,394.

Specification of Letters Patent.

Patented Nov. 21, 1905.

Application filed January 26, 1905. Serial No. 242,784.

To all whom it may concern:

Be it known that I, EDWIN C. WASHBURN, a citizen of the United States, residing at Minneapolis, in the county of Hennepin and State of Minnesota, have invented certain new and useful Improvements in Draft-Rigging for Cars; and I do hereby declare the following to be a full, clear, and exact description of the invention, such as will enable others skilled in the art to which it appertains to make and use the same.

My invention relates to draft-rigging for cars, and has for its especial object to provide a draft-rigging suitable for street-cars or cars of lighter draft than usually employed by railway systems.

To the above ends the invention consists of the novel devices and combinations of devices hereinafter described, and defined in the claims.

The invention is illustrated in the accompanying drawings, wherein like characters indicate like parts throughout the several views.

Figure 1 is a side elevation showing a portion of a car and showing my improved draft-rigging applied thereto, some parts of said rigging being sectioned on the line $x' x'$ of Fig. 2. Fig. 2 is a plan view of the draft-rigging removed from the car and some parts being broken away. Fig. 3 is a transverse vertical section taken on the line $x^3 x^3$ of Fig. 1. Fig. 4 is a view, partly in side elevation and partly in section, illustrating a modified construction of the improved draft-rigging; and Fig. 5 is an end elevation of the parts shown in Fig. 4.

The numeral 1 indicates one of the floor-timbers of the car-body, to which in the construction illustrated in Figs. 1, 2, and 3 a flanged draft-bracket 2 is bolted or otherwise rigidly secured. This draft-bracket 2 at its outer end has vertically-spaced ears 3, through which is passed a coupling-pin 4. Rigidly secured to the timber 1, near its outer end, is a suitable rest-bracket or draft-bar support 5, which may be of the usual construction, arranged to support the draft-bar and to permit vertical and lateral movements thereof.

The numeral 6 indicates the draft-bar of the coupler, the coupler-head being broken away. The coupler-head may be of the Master Car-Builders' type or of any other form, so far as my present invention is concerned. At its inner end the draft-bar 6 is

provided with a projecting bolt-like stem or draft-bar extension 7, the end of which is threaded and engages a nut 8. As shown, the inner end of the bar 6 is bifurcated to receive the flattened end of the stem 7, and the said parts are rigidly united by heavy rivets 9.

The numeral 10 indicates a spring case or housing which forms one section of the draft-rigging and at its inner end is provided with a heavy lug 11, that works between the lugs 3 of the draft-bracket 2 and is pivotally attached thereto by the coupling-pin 4. The upper portion of the housing 10 is semicylindrical; but the sides of the lower portion thereof extend vertically downward, so as to leave a large opening 12 in the bottom of said housing, through which the draft-spring 13 may be passed. The nut 8 on the draft-bar stem 7 is held against rotation, but is permitted a sliding movement longitudinally of the car, by a hub-like extension 14, formed at one end of the casing 10 and loosely but quite closely fitting the said nut. On the stem 7 of the draft-bar is a pair of followers 15 and 16, the former of which normally engages the nut 8 and the bearing formed by the adjacent end of the housing 10, and the latter of which normally engages the bearing formed by the other end of said housing and is provided with a sleeve-like hub 16^a, that projects through said casing for engagement with the bearing-shoulder afforded by the end of the draft-bar 6. The spring 13 surrounds the stem 7 and is compressed between the followers 15 and 16.

With the construction described it is evident that under draft strains the nut 8, acting on the follower 15, will move the same away from its bearing on the adjacent end of the housing 10 and will compress the spring 13 against the follower 16, which then becomes a fixed base of reaction. The clearance between the coils of the spring 13 is preferably such that under a maximum compression strain the nut 8 will not be drawn out of its seat in the hub 14 of the housing 10. Under bumping strains the follower 16 moves away from the bearing afforded by the outer end of the housing 10 and compresses the spring 13, the follower 15 then becoming the fixed base of resistance to the spring. Inasmuch as the nut 8 cannot rotate and inasmuch as the flat lower surface of the draft-bar 6 rests upon a flat support, it is evident that there will be no accidental or uninten-

tional rotary movements of the draft-bar and the nut with respect to each other, and hence that they will maintain any relative adjustment in which they may be set. However, 5 by lifting up the draft-bar from its support it is possible to rotate the same, thereby varying the position of the nut on the stem 7 and taking up any slack which may from time to time occur between the parts. In the construction described the followers, the housing, and the spring maintain an axial alignment with the draft-bar and move therewith when the draft-bar is moved transversely of the car. By this arrangement, therefore, all 15 draft and bumping strains are delivered to the spring 13 and to the followers and housing on a line coincident with their common axes.

In the modified construction illustrated in 20 Figs. 4 and 5 the housing 10 is cast integral with a flanged bracket 10^a, which is adapted to be directly bolted to the timbers or beams of the car-body, and the lug 11 of said housing is dispensed with. Again, the stem 7 at 25 its forward end instead of being rigidly secured to the draft-bar 6 is pivoted thereto, and for this purpose is provided with a bifurcated head 7^a, that embraces a reduced lug on the end of said draft-bar. A coupling-pin 30 4^a pivotally connects the head 7^a to said draft-bar.

The draft-rigging above described is of small cost, is very strong and durable, and is in all respects highly satisfactory for the purposes had in view.

It will of course be understood that the rigging described is capable of modification within the scope of my invention as herein set forth and claimed.

40 What I claim, and desire to secure by Letters Patent of the United States, is as follows:

1. In a draft-rigging, the combination with a draft-bar and a stem or bolt applied thereto, and having, at its projecting end, a nut, of a

pair of followers on said stem or bolt between 45 said nut and the draft-bar proper, a spring compressed between said followers, and a housing inclosing said spring and followers, affording bases of reaction for said followers, and having a seat in which said nut is free for 50 sliding movements, but is held against rotation, substantially as described.

2. In a draft-rigging, the combination with a draft-bar 6 and a support with which the flat lower surface thereof normally engages, 55 of a stem 7 attached to said draft-bar, the nut 8, engaging the end of said stem, the followers 15 and 16 on said stem, the spring 13 between the said followers, and the housing 10 embracing said spring and followers, and affording bases of reaction for said followers, said housing having an opening 12 in its bottom, and having a recessed hub portion 14 in which said nut 8 is free to slide but is held against rotation, substantially as de- 60 scribed.

3. The combination with a draft-bar support 5, and a bracket 2, both secured to a car-body, of a draft-bar 6 having the rigidly-attached stem 7, the nut 8 on the end of said stem, the followers 15 and 16 on said stem, the latter having a hub 16^a engageable with the end of said draft-bar, the spring 13 interposed between said followers, and the housing 10 inclosing said spring and followers, and affording bases of reaction for said followers, said housing having an opening 12 in its bottom, and a recessed hub portion 14 in which said nut is free to slide but is held against rotation, said hub having a projecting lug 11 pivotally connected to said bracket 2, substantially as described.

In testimony whereof I affix my signature in presence of two witnesses.

EDWIN C. WASHBURN.
